UNITED STATES PATENT OFFICE.

WILLIAM WHITWORTH, OF WORCESTER, MASSACHUSETTS.

GRATE.

SPECIFICATION forming part of Letters Patent No. 478,775, dated July 12, 1892.

Application filed October 6, 1891. Serial No. 407,892. (No model.)

To all whom it may concern:

Be it known that I, WILLIAM WHITWORTH, of the city of Worcester, in the county of Worcester and State of Massachusetts, have 5 invented certain new and useful Improvements in Grates; and I hereby declare that the following is a full, clear, and exact description of the same, reference being had to the accompanying drawings, forming part of this 10 specification.

This invention has reference to improvements in furnace-grates.

The object of this invention is to produce a furnace-grate in which the bars may be operated to shake the ashes from beneath the fire supported on said grate.

The further object of my invention is to produce a grate having independently-operated bars which may be turned to dump the 20 fire into the ash-pit.

The invention consists in the novel construction of the grate-frame and the combination therewith of the peculiar form of grate-bars pivoted thereto, and suitable mechanism for 25 operating said bars and the grate-frame, as will be more fully described hereinafter, and pointed out in the claims.

Figure 1 represents a vertical sectional view of a portion of a furnace, showing the grate 30 in position and indicating the operation of the same. Fig. 2 is a cross-sectional view of the same, portions of the grate-bars being broken away to show the operating-cams. Fig. 3 represents a view of one end of a center 35 grate-bar, showing the cams carried by a shaft and the shaker-handle inserted in a slot provided in the arm of the cam-shaft.

Similar numbers of reference designate corresponding parts throughout.

40 In the drawings, 5 indicates a strong iron frame adapted to sustain the grate-bars and the weight of the fire carried thereon. The sides of this frame 5 are provided with shafts 6, which are journaled in suitable bearings 45 supported in the furnace-walls, the outer ends of either or both of these shafts being square to engage with a corresponding socket of a crank-handle by which the grate may be dumped, the rear end of this frame being supported by the brackets 7, secured to the rear 50 wall of the furnace, while the front end of the frame is supported by the sliding rod 8,

which may be operated from the front of the furnace.

At or near the longitudinal center of the 55 frame 5 is secured a shaft 9, on which the grate-bars 10 are journaled, each bar having a reinforced bearing 11 of sufficient thickness to separate the bars, the ends of which are also reinforced in thickness to an equal 60 extent. The front end of each of these bars 10 is provided with the circular perforation 12 and cam-slots 13 and 14, extending through the thickness of the reinforced end of the bar, and the two center bars have corresponding 65 segmental slots 15, through which the arm of the cam-shaft extends. The ends of the cam-shaft 16 are journaled in bearings near the front end of the frame 5, and the shaft extends through the circular perforations in the 70 grate-bars, having cams 17 and 18 working in the cam-slots 13 or 14 of alternating grate-bars, the cams 17 working in the slots 13, while the cams 18 work in the slots 14, so that when the shaft 16 is partially revolved the 75 cams lift and depress the alternate grate-bars. The arm 19 is formed in part with or may be secured to the shaft 16 and depends therefrom, extending through the segmental slots 15 in the central bars and having a slot at its 80 lower end, in which the inner end of the shaker-handle 20 engages and may be secured. By means of this handle 20 the shaft 16 is partially revolved first in one direction and then in the other, alternately lifting and depressing 85 the grate-bars, as shown in Fig. 1, and shaking the ashes from beneath the fire.

It is obvious that the grate-bars 10 may be single, as shown, or two or more may be combined into one without departing from the 90 spirit of my invention. In such case the cams 17 and 18 would be placed farther apart on the shaft and each duplex grate-bar would be operated in the same manner as the single ones.

Having thus described my invention, I 95 claim as new and desire to secure by Letters Patent—

1. In a grate, the combination, with a suitable frame and a series of grate-bars pivoted on a shaft secured in said frame and having 100 cam-slots formed in the front portions thereof, of a pivoted shaft extending through perforations in the bars and having cams adapted to co-operate with the slots of the alter-

nate bars and means for operating said shaft, as described.

2. The combination, with a grate-frame and the bars 10, pivoted on the shaft 9, secured 5 therein, and having the circular perforations 12 and cam-slots 13 and 14, of a shaft journaled in said frame, extending through said perforations 12, and having cams 17 and 18,

a depending arm 19, secured to said shaft, and a shake-handle 20, extending therefrom, 10 adapted to rock said shaft 9, as and for the purpose described.

WILLIAM WHITWORTH.
